(57) **CLAIM**

The ornamental design for a cabinet with sink, as shown and
described.

DESCRIPTION

FIG. 1 is a front perspective view of a cabinet with sink,
showing our new design.

FIG. 2 is a front elevation view thereof.

FIG. 3 is a rear elevation view thereof.

FIG. 4 is a first side elevation view thereof.

FIG. 5 is a second side elevation view thereof.

FIG. 6 is a top plan view thereof.

FIG. 7 is a bottom plan view thereof.

FIG. 8 is a front perspective view of a cabinet with sink,
without obscurement.

FIG. 9 is a front elevation view thereof.

FIG. 10 is a rear elevation view thereof.

FIG. 11 is a first side elevation view thereof.

FIG. 12 is a second side elevation view thereof.

FIG. 13 is a top plan view thereof; and,

FIG. 14 is a bottom plan view thereof.

The broken lines shown in the drawing views are for
illustrative purposes and form no part of the claim design.
